DESIGN FOR A FOLDING LAMP SHADE

Arthur K. Lueders, St. Paul, Minn.

Application April 10, 1942, Serial No. 106,520

Term of patent 3½ years

To all whom it may concern:

Be it known that I, Arthur K. Lueders, a citizen of the United States, residing at St. Paul, in the county of Ramsey, and State of Minnesota, have invented a new, original, and ornamental Design for a Folding Lamp Shade, of which the following is a specification, reference being had to the accompanying drawing, forming part thereof.

I claim:

The ornamental design for a folding lamp shade, as shown.

ARTHUR K. LUEDERS.
